UNITED STATES PATENT OFFICE

130,253

DESIGN FOR A RANGE WELL COOKER

George C. Pearce, Dayton, Ohio, assignor to General Motors Corporation, Dayton, Ohio, a corporation of Delaware

Application June 9, 1941, Serial No. 101,355

Term of patent 14 years

To all whom it may concern:

Be it known that I, George C. Pearce, a citizen of the United States, residing at Dayton, in the county of Montgomery and State of Ohio, have invented a new, original, and ornamental Design for a Range Well Cooker, of which the following is a specification, reference being had to the accompanying drawing, forming part thereof.

In the drawing:

Fig. 1 is a front elevational view of the range well cooker showing my new design;

Fig. 2 is a top plan view of the same; and

Fig. 3 is an enlarged fragmentary sectional view thereof taken along the line 3—3 of Fig. 2.

I claim:

The ornamental design for a range well cooker, as shown.

GEORGE C. PEARCE.
